UNITED STATES PATENT OFFICE.

ANSON J. BACON, OF HALLOWELL, MAINE.

HOLDBACK FOR VEHICLES.

SPECIFICATION forming part of Letters Patent No. 251,814, dated January 3, 1882.

Application filed November 5, 1881. (No model.)

To all whom it may concern:

Be it known that I, ANSON J. BACON, of Hallowell, in the county of Kennebec and State of Maine, have invented a new and useful Improvement in Spring-Holdbacks for Vehicles, of which the following is a full, clear, and exact description.

Reference is to be had to the accompanying drawings, forming part of this specification, in which similar letters of reference indicate corresponding parts in both the figures.

Figure 1 is a side elevation of my improvement, illustrating its use. Fig. 2 is a plan view of the improvement.

15 The object of this invention is to provide holdbacks constructed in such a manner that the first resistance to the forward pressure of the vehicle will be elastic or yielding, so as to prevent any jar to the vehicle or horse.

20 The invention consists in holdback-tugs made in the manner hereinafter described, and adapted to connect the harness-breeching with the draft-spring, and also in the combination, with the draft-spring, the holdback-irons, and the harness-breeching, of holdback-tugs, whereby the strain on the holdback-tugs will be of an elastic nature and will be resisted by the draft-spring, as will be hereinafter fully described.

30 A represents the thills of a vehicle, to the rear side of the cross-bar of which is secured the center of a curved or half-elliptic spring, B, by a clip, C, or other suitable means. Through holes in the end parts of the cross-bar of the thills A pass bolts D, which also pass through holes in the ends of the spring B, and have nuts screwed upon them.

Upon the forward ends of the bolts D are formed hooks, upon which are hooked the ends

of the tugs E and the ends of the holdback-tugs F. The holdback-tugs F pass through holdback-irons G attached to the thills A, and their other ends are connected with the breeching H of the harness.

For convenience rings I can be attached to 45 the ends of the holdback-tugs F, one to hook upon the hook of the bolt D and the other to receive a snap-hook, J, connected with the breeching, so that the horse can be readily connected with and disconnected from the 50 thills A. With this construction the strain in holding back is applied to the hook-bolts D, to which the draft-strain is applied, and which are connected with the ends of the spring B, so that the first application of the draft-strain 55 and of the holding-back strain will be resisted by the elasticity of the spring B, and thus all jars from the forward impulse of the vehicle will be avoided.

Having thus described my invention, I claim 60 as new and desire to secure by Letters Patent—

1. The combination, with the thills A, provided with the holdback-irons G and the holdback-tugs F, of the spring B, secured to the rear of the cross-bar of the thills, and the hooks 65 D, substantially as and for the purpose set forth.

2. The combination, with the draft-spring B, holdback-irons G, and harness-breeching H, of the holdback-tugs F, substantially as herein 70 shown and described, whereby the strain on the holdback-tugs will be of an elastic nature and will be resisted by the draft-spring, as set forth.

ANSON J. BACON.
